UNITED STATES PATENT OFFICE.

CHARLES B. ULRICH, OF WAUSAU, WISCONSIN.

ADVERTISING-SIGN.

1,076,250.

Specification of Letters Patent.

Patented Oct. 21, 1913.

Application filed May 15, 1912. Serial No. 697,368.

To all whom it may concern:
Be it known that I, CHARLES B. ULRICH, a citizen of the United States, residing at Wausau, in the county of Marathon and 5 State of Wisconsin, have invented certain new and useful Improvements in Advertising-Signs, of which the following is a full, clear, concise, and exact description, reference being had to the accompanying drawings, forming a part of this specification.

My invention relates to an improved advertising sign which may be employed to advantage for temporary advertising in connection with show windows, show-cases, 15 etc., where it is frequently advisable to secure small pasteboard or cardboard signs to the inner or under surface of the glass on the window or show-case, so as to attract the attention of passers-by and observers to 20 some particular article that is being specially offered for sale.

By my invention I employ in combination a sheet of suitable material for receiving the advertising matter on one of its 25 faces, which material may be of any desired kind, as pasteboard, cardboard, thick paper, or even thin light metal, and a device for securing the advertising sheet to the surface of the glass, said device comprising 30 preferably a vacuum cup formed of very flexible resilient material, such as india rubber, which cup is provided with a spring arm or arms for engaging the advertising sheet to hold it in place. The advertising 35 sheet is prepared with an aperture through it so that the devices connected with the vacuum cup may engage the back of the advertising sheet, while the cup itself is in engagement with the glass through said 40 aperture.

The several drawings illustrating my invention are as follows:

Figure 1 shows a back view of a sign and device for holding it in place upon a plate 45 of glass. Fig. 2 shows a front view of the sign held in place, as indicated in Fig. 1. Fig. 3 is a sectional view of the parts shown in Fig. 1, taken along the line 3—3. Fig. 4 is an edge view of the advertising sign, 50 showing its relation to the glass when the vacuum cup is out of engagement with the glass. Fig. 5 shows in plan view a modified construction of spring connected with the vacuum cup for engaging the sign. Fig. 6 55 shows in side view the vacuum cup shown

in Fig. 5 in position to hold a sign in place against a plate of glass.

As shown in Figs. 1, 2, 3 and 4, the advertising sign 1 may have any desired conformation, although it is attractive and convenient to have it circular, as indicated, and this sign may be made of any desired material having advertising matter upon its face which will show through the plate of glass 2, as indicated in Fig. 2. The sign 1 is 60 provided with a central aperture 3 so that a vacuum cup 4 of flexible material, as india rubber, may pass through it to engage the under surface of a glass plate of a show-case or the inner surface of the glass of a 65 show window. The vacuum cup 4 carries a spring strip 5, which is secured to said cup by a small bolt 6, the ends of the spring strip being curved outward slightly, as indicated in Figs. 3 and 4, so as to rest against the back face of the sign without tearing the same. The strip 5 is engaged by retaining loops or bands 7 secured to the back 70 face of the sign 1, through which loops the ends of the strip 5 pass, as a result of which the parts are retained in proper position. When the vacuum cup is released from the glass, the strip 5 may readily be removed from one sign and inserted in another by 75 sliding the strip 5 endwise through the loops.

In the modified construction shown in Fig. 6, the strip 5 is replaced by a spiral spring 8 which is secured to the vacuum cup 4^a in much the manner shown and described above for the securing of the strip 5 to the vacuum cup 4. The spring 8 by engaging the advertising sign 9 through an entire circle serves to hold the sign more firmly in place, particularly if the sign is of 80 relatively thin material, than is the case with the single strip of spring metal shown 85 in Figs. 1 to 4 inclusive.

While I have shown my invention in the particular embodiment above described, it 90 will be understood that I do not limit myself to any particular way of securing the results indicated except as limited by the scope of the appended claims. The sign may have any desired conformation and the vacuum cup may be provided with any desired form of spring mechanism for engaging the sign to hold it in place, and the relation between the sign and the devices carried by the vacuum cup may be of any kind 95 100 105 110

that will accomplish the results described above within the limits of the appended claims.

What I claim is:

5. 1. In combination, a support, an advertising sign having an aperture therethrough, a vacuum cup of flexible material for passing into the aperture and contacting with said support, and a spring secured to the 10 cup for pressing the sign into engagement with said support when the cup is in place in said aperture.
15. 2. In combination, a support, an advertising sign comprising a sheet of material adapted to receive advertising matter upon one of its faces and provided with an aperture therethrough, and a vacuum cup support passing through said aperture and contacting with said support, said sign being adapted to be engaged and supported by 20 devices carried by said vacuum cup, thus pressing the sign into engagement with said support.

3. In combination, an advertising sign having an aperture therethrough, a vacuum cup, a spring secured to said cup, and loops upon said sign through which said spring is arranged to have sliding engagement, said cup being adapted to pass through said aperture. 25

4. An advertising sign comprising a circular sheet adapted to receive advertising material on one of its faces and having an aperture through it, a supporting vacuum cup extending through said aperture, a 30 spring fastened to said cup and engaging said sign, and bands extending from said sign and engaging said spring, and arranged so that said spring may be readily withdrawn therefrom. 40

In witness whereof, I hereunto subscribe my name this 10th day of May, A. D., 1912.

CHARLES B. ULRICH.
